FIG. 2

FIG. 3

INVENTOR:

Truman H. Forrest

BY

Pierre Barnes

ATTORNEY

UNITED STATES PATENT OFFICE.

TRUMAN H. FORREST, OF SEATTLE, WASHINGTON.

DESIGN FOR A PORTABLE LIQUID-DISPENSING APPARATUS.

60,090.

Specification for Design.

Patented Dec. 27, 1921.

Application filed July 27, 1921. Serial No. 488,019. Term of patent 14 years.

To all whom it may concern:

Be it known that I, TRUMAN H. FORREST, a citizen of the United States, residing at Seattle, in the county of King and State of Washington, have invented a new, original, and ornamental Design for a Portable Liquid-Dispensing Apparatus, of which the following is a specification, reference being had to the accompanying drawings, forming a part thereof.

Figure 1 is a side elevation; Fig. 2 is a front elevation; and Fig. 3 is a plan view of a portable liquid dispensing apparatus showing my new design.

I claim:

The ornamental design for a portable liquid dispensing apparatus, as shown.

Seattle, Washington, July 18th, 1921.

TRUMAN H. FORREST.
